SPEED CORRECTION IN TELEGRAPH CIRCUITS

James A. Spencer, Teaneck, N. J., assignor to Radio Corporation of America, a corporation of Delaware

Application June 26, 1943, Serial No. 492,371

10 Claims. (Cl. 178—53)

This invention relates to the correction of speed or phase displacements in multiplex telegraph and analogous circuits.

An object of the invention is to produce a more accurate phase or speed adjustment of distributor brushes with simplified circuits.

Other objects of the invention will appear in the following description, reference being had to the drawing, in which:

The single figure of the drawing diagrammatically illustrates one embodiment of the invention, a signal graph being shown at the top of the figure to illustrate the phase relation.

Referring to the drawing, the multiplex signals transmitted from a distant point arrive over line L and pass through the coils of relay 1 to ground. It may be considered, by way of example, that the signals are of the plus-and-minus type and that this relay is a polar relay, though, of course, it may be used for on-and-off signals, as will be apparent to those skilled in the art.

The tongue 2 of the relay is connected through resistor 3 to power, say the positive terminal 4. The tongue 2 is biased to center position and swings against the mark contact 5 on receipt of, say, a positive signal and against the space contact 6 on receipt of a negative signal. The mark contact 5 is connected through the coil of pulse-forming relay 7 to ground. It is also connected to the tongue 8 of this relay, normally engaging contact 9, which is connected to solid local ring 10 of a multiplex distributor 11 serving a plurality of channels. A portion, only, of the distributor 11 is shown, as the number of channels is immaterial insofar as my invention is concerned.

The distributor 11 has, in addition to the ring 10, a segmented local ring 12, a solid signal ring 13 and a segmented signal ring 14. Distributor arm 15 has a pair of conductively connected brushes 16, 17 sweeping over rings 10 and 12. The distributor arm 15 also carries a second pair of electrically connected brushes 18, 19 sweeping over the signal rings 13 and 14, respectively. The pairs of brushes 16, 17 and 18, 19 are insulated from each other and from other portions of the distributor arm. The segments of rings 12 and 14 are of equal angular length.

The segments of the signal ring 14 are half the length of the signal pulses 20, as shown in graph S at the top of the figure of the drawing. Alternate segments, as indicated at 21, are connected to the printing or recording apparatus (not shown) by conductors 22. Most of the other alternate segments 23 of ring 14 may be consid-

ered as idle or dead, though a few are used for special signals, the purpose of which is immaterial as far as this invention is concerned.

Segmented local ring 12 has as many segments as there are segments in the signal ring 14. Every alternate segment in ring 12 is designated as an *a* segment and these are joined together electrically. The other alternate segments are designated by reference character *b* and these are likewise joined together electrically. The rings 12 and 14 are so constructed that the insulating segment between the *a* and *b* segments is in line with the centers of the segments of the signal ring 14: that is, the phasing is such that the center of the brush 17 is at the dividing line of the *a* and *b* segments when the center of the brush 19 is at the center of the segments of the signal ring 14.

The segments *a* are connected to the tongue 24 of relay 25 and through its operating coil 26 to ground. The segments *a* are also connected to the tongue 27 of relay 28. The operating coil 29 of relay 28 has one terminal connected to the positive terminal 30 of the supply source and the other terminal is connected to contact 31, which cooperates with tongue 24 of relay 25. The other contact 32 of relay 25 is connected to ground, which may, for example, be the plus-minus terminal of the battery source. Tongues 24 and 33 of relay 25 are adapted to engage contacts 31 and 32, respectively, when its coil 26 is energized and to break therewith when de-energized.

Segments *b* of the distributor are connected to tongue 34 of relay 35 and also through its operating coil 36 to ground, as well as to the tongue 37 of relay 38. The coil 39 of relay 38 is connected between the positive terminal 40 of the supply source and contact 41 of relay 35. The contact 42 of relay 38 and the contact 43 of relay 35 are connected to ground.

When the coil 36 of relay 35 is energized, its tongues 34 and 44 engage the contacts 41 and 43, respectively. Likewise, when the coil 39 of relay 38 is energized, it engages the contact 42 and disengages therefrom when the coil is de-energized.

The distributor arm 15 is rotated in approximate synchronism and phase with the distributor arm at the distant station by any of the well-known synchronizing systems, but by way of example it may be assumed to be rotated by the rotor 45 of a synchronous motor 46, energized from a standard frequency source F having a voltage maintained in approximate synchronism and phase with that of the source at the distant

station with which communication is being maintained. Exact phase is produced by rotating the field 47 forwards or backwards by an auxiliary motor 48 until correct phase is established, as will be understood. A worm and gear connection 49 between the motor 48 and the field 47 is shown diagrammatically in the drawing, but any other arrangement may be used, as this is indicative only.

The motor 48 is shown as a direct current motor, but this again is indicative only. One brush of this motor is connected to the positive source of the supply and the other brush is connected to one terminal of field coils 50 and 51. The other terminal of field coil 50 is connected to tongue 33 of relay 25 and the remaining terminal of field coil 51 is connected to tongue 44 of relay 35. Field coil 50 is energized oppositely to field coil 51, so that when relay 25 is operated, motor 48 rotates in one direction and when relay 35 is operated, it rotates in the opposite direction. In both cases it operates as a series motor, though obviously it could be connected to perform the same action as a shunt or other type of motor.

The operation of my invention will now be described:

The adjustment is such that at exact phase and synchronism the center of signal segments 21 in succession will be engaged by brush 19 at the center of signal pulses 20. At such time brush 17 will engage both segments *a* and *b* of ring 12, as the brushes are wider than the separating insulation. This means that brush 17 will also be in engagement with both segments *a* and *b* at the start of the signal pulses 20 when the brush 19 is at the center of idle segments 23.

Suppose, however, true phase relation is departed from, so that the distributor arm 15 is lagging the received signals. Brush 17 will then be in engagement with segment *a* and out of engagement with the segment *b* when the signal pulses 20 start. When the tongue 2 of relay 1 engages its mark contact 5 at the commencement of the signal marks 20, current flows through tongue 8 and contact 9, ring 10 and brushes 16, 17 and through coil 26 of relay 25 to ground. This flow of current is interrupted by energization of the relay 1, which opens the circuit at tongue 8 and contact 9, but before this circuit is opened, the engagement of contact 31 of relay 25 closed a holding circuit from the positive terminal 30 through coil 29 of relay 28, contact 31, tongue 24 and coil 26 to ground. Relay 25 therefore remains energized after the pulse-forming relay 1 opens the circuit. Relay 28 is slow-acting due to shunt condenser 53 and series resistance 54 and before it operates its switch tongue 27, a circuit is closed from the positive terminal through the armature of motor 48, field 50, tongue 33 and contact 32 to ground. This moves the field 47 of synchronous motor 46 forward, which also advances the rotor 45 and decreases the lag of the distributor arm 15. When slow-acting relay 28 moves its switch tongue 27 against its contact 55, the coil 26 of relay 25 is short-circuited and correction motor 48 is de-energized by the opening of the circuit at 32, 33.

By way of example, relays 28 and 38 may be adjusted to move their tongues into engagement with their contacts so as to give an optimum release of the armatures of relays 25 and 35 in seventy-five milliseconds.

There can be only one pulse formed during a mark period, because relay 1 remains energized throughout the mark. Relay 1 is de-energized

at the start of the space and the process is repeated at the start of the succeeding mark signal, until the lag of the distributor arm 15 is corrected. Thus, the speed of the distributor arm 15 will be repeatedly kicked forward until correct phase results. When this happens brush 17 will rest on both an *a* segment and a *b* segment when the mark signal starts. This closes a circuit through both the coils 26 and 36 of relays 25 and 35, respectively, and the short pulse cannot energize both these relay coils sufficiently to move their tongues against their contacts. Consequently, there can be no energization of the correction motor 48 so long as exact phase condition exists.

If the distributor arm 15 leads the received signals, the brush 17 will be on a *b* segment and out of engagement with an *a* segment when the mark signal starts. This will energize relay 35 and close the circuit through the armature to the correction motor and field 51 to ground. Since field 51 is energized in a reverse direction, the motor will revolve in the opposite direction and retard the rotor 45 to decrease the lead.

Timing relay 38 short-circuits coil 36 of relay 35 and stops the correcting action after the desired period of delay. This correcting action will be repeated until the distributor arm 15 is in exact phase with the received signals, at which time brush 17 will engage both segment *a* and segment *b* of ring 12 at the start of the signal pulses, which will prevent operation of relays 25 and 35, as already explained.

By regulating the capacities 53 in shunt with coils 28 and 38 or the resistances 54 in circuit therewith, the timing may be so arranged as to adjust the closure of the tongues 27 and 37 with their contacts 32 and 42 after the desired interval of time has elapsed and thus the length of time of the energization of the correction motor 48 can be adjusted to best operating condition.

If the brushes are slightly less in width than the insulation between segments *a* and *b*, a condition somewhat difficult to meet in practice, then the brushes would never engage both segments simultaneously and there would be no current in relays 25 and 35 at true phase, but the action and results would be identical to that already described. Also, the relays can be constructed to operate their switches on receiving the major portion of the pulse energy instead of all of it. This brings them into operation with less departure from synchronism or phase.

Having described my invention, what I claim is:

1. In speed correction for multiplex telegraph circuits, a speed correcting circuit, means for producing current pulses at predetermined points of the signals, a control relay energized by said pulses for closing said speed correcting circuit, a timing relay acting to de-energize the first relay and means for delaying the de-energizing action of the timing relay.

2. In speed correction for multiplex telegraph circuits, a speed correcting circuit, means for producing current pulses at predetermined points of the signals, a control relay energized by said pulses for closing said speed correcting circuit, a timing relay having a switch, a holding circuit for said control relay connected to said switch, said control relay being de-energized upon operation of said switch by the timing relay and means for delaying the operation of the switch by the timing relay.

3. In speed correction for multiplex telegraph

circuits, a speed correcting circuit, means for producing current pulses at predetermined points of the signals, a control relay energized by said pulses for closing said speed correcting circuit, a holding circuit for said relay, a timing relay having a switch and being energized through the switch of the first relay, a holding circuit for said control relay connected to said switch, said control relay being de-energized upon operation of said switch by the timing relay and means for delaying the operation of the switch by the timing relay.

4. In speed correction for multiplex telegraph circuits, a speed correcting circuit, means for producing current pulses at predetermined points of the signal, a control relay energized by said pulses for closing said speed correcting circuit, a holding circuit for said relay, a timing relay energized by the switch of the first relay and having a switch adapted to short-circuit said holding circuit to de-energize the first relay and means for delaying the operation of the second switch by the timing relay.

5. In phase correction for multiplex telegraph circuits, a speed increasing circuit, a speed decreasing circuit, separate control relays having switches in said circuits, means for producing current pulses at predetermined points of the signals, means for causing said pulses to pass through the circuits of both of said control relays at correct phase of the signal and through the circuit of one only at incorrect phase, said control relays being able to close their switches only upon receiving the major part of the energy of said pulses and means energized by said control relays for producing their de-energization a predetermined time thereafter.

6. In phase correction for multiplex telegraph circuits, a speed increasing circuit, a speed decreasing circuit, separate control relays having switches in said circuits, means for producing current pulses at predetermined points of the signals, means for causing said pulses to pass through the circuits of both of said control relays at correct phase of the signal and through the circuit of one only at incorrect phase, said control relays being able to close their switches only upon receiving the entire energy of said pulses and means energized by said control relays for producing their de-energization a predetermined time thereafter.

7. In phase correction for multiplex telegraph circuits, a speed increasing circuit, a speed decreasing circuit, separate control relays having switches in said circuits, means for producing current pulses at predetermined points of the

signals, means for causing said pulses to pass through the circuits of both of said control relays at correct phase of the signal and the major part thereof through the circuit of one only at incorrect phase, said control relays being able to close their switches only upon receiving the major part of the energy of said pulses, separate timing relays acting to de-energize the first-mentioned relays and means for delaying the de-energization action of the timing relays.

8. In phase correction for multiplex telegraph circuits, a speed increasing circuit, a speed decreasing circuit, separate control relays having switches in said circuits, means for producing current pulses at predetermined points of the signals, means for causing said pulses to pass through the circuits of both of said control relays at correct phase of the signal and through the circuit of one only at incorrect phase, said control relays being able to close their switches only upon receiving the entire energy of said pulses, separate timing relays acting to de-energize the first-mentioned relays and means for delaying the de-energization action of the timing relays.

9. In phase correction for multiplex telegraph circuits, a speed increasing circuit, a speed decreasing circuit, a first control relay having a switch in said speed increasing circuit, a second control relay having a switch in said speed decreasing circuit, means for producing current pulses at predetermined points of the signals, means for causing said pulses to pass through the circuits of both of said control relays at correct phase of the signal, through the first control relay with lagging signal phase and through the second control relay with leading signal phase and means energized by said control relays for producing their de-energization a predetermined time thereafter.

10. In phase correction for multiplex telegraph circuits, a speed increasing circuit, a speed decreasing circuit, a first control relay having a switch in said speed increasing circuit, a second control relay having a switch in said speed decreasing circuit, means for producing current pulses at predetermined points of the signals, means for causing said pulses to pass through the circuits of both of said control relays at correct phase of the signal, through the first control relay with lagging signal phase and through the second control relay with leading signal phase, separate timing relays acting to de-energize the first-mentioned relays and means for delaying the de-energization action of the timing relays.

JAMES A. SPENCER.
